(57) CLAIM

The ornamental design for a watch device, as shown and described.

DESCRIPTION

FIG. 1 is a front, bottom and right side perspective view of a watch device showing our new design;

FIG. 2 is a top, front and left side perspective view thereof;

FIG. 3 is a front elevation thereof;

FIG. 4 is a right side elevation thereof;

FIG. 5 is a left side elevation thereof;

FIG. 6 is a rear elevation thereof;

FIG. 7 is a bottom view thereof; and,

FIG. 8 is a top view thereof.

Portions of FIGS. 1 through 8 are shown in dashed lines for illustrative purposes only and form no part of the claimed design.

1 Claim, 4 Drawing Sheets
